 Atty.

UNITED STATES PATENT OFFICE.

ALFRED CHARLES ATKINSON, OF WELLINGTON, NEW ZEALAND.

DEVICE FOR HEATING METAL-CASTING MOLDS.

1,280,631.

Specification of Letters Patent.

Patented Oct. 8, 1918.

Application filed October 3, 1917. Serial No. 194,580.

To all whom it may concern:

Be it known that I, ALFRED CHARLES ATKINSON, subject of the King of Great Britain, residing at Wellington, New Zealand, have invented new and useful Improvements in Devices for Heating Metal-Casting Molds; and I do hereby declare the following to be a full, clear, and exact description of the same.

10 This invention has been designed in order to provide improvements in the heating of the molds used for casting small metal articles, and particularly used for casting artificial dentures and other dental work. 15 These molds are formed by positioning a fusible wax model or pattern of the article to be cast in a metal flask and surrounding it with an investment of plaster of Paris composition. This mold is then heated to 20 melt the model so that the material of which it is composed will disappear and leave a mold of corresponding shape into which the metal is run to form the casting the mold being heated to insure of the proper running 25 of the molten metal under the pressure usually employed in this class of casting.

In the operation of this process, it is advisable that the mold should first be slowly heated to melt the fusible model or pattern 30 and to expel the moisture from the investment material, as its subjection to a quick heat renders it liable to uneven drying and consequently the destruction or distorting of the mold. After the moisture has been 35 expelled the heat may be raised to heat the mold to the necessary degree to provide for the effective running of the metal.

The invention consists in means whereby these operations of the initial slow heating 40 and the subsequent quick heating to a high degree, may be effectively carried out, and also embodies means whereby a visible indication may be given the operator when the mold has been first sufficiently heated to expel the moisture and then heated to the predetermined degree necessary for the casting. This feature of the invention is adapted to be used in conjunction with the indicating means described in the specification of my 45 application for Patent No. 123,143, dated 30th September, 1916, and which consists in a rod of material fusible at a higher temperature than that to which the mold is to be heated, that is embedded at one of its ends 50 in a plug of a material fusible at the tempera-

ture to which the mold is to be raised for casting purposes. The plug is positioned within the investment material of the mold and its rod extends centrally in a tunnel leading to the outside of such material. 60 When the plug melts the rod is released and falls to one side of the tunnel thereby indicating the fact that the desired temperature has been reached.

In fully describing the invention reference will be made to the accompanying sheet of drawings, in which:—

Figure 1 is a sectional elevation of a molding flask ready for heating in the furnace.

Fig. 2 is a plan of the lower part of the 70 furnace.

Fig. 3 is an end elevation of the furnace.

Fig. 4 a side elevation thereof.

Fig. 5 is a sectional end elevation, and

Fig. 6 a sectional side elevation thereof, 75 the molding flask being shown in position in each figure.

Referring first to Fig. 1, A represents the molding flask that is made of metal and of any approved shape in cross section but generally of circular or elliptical shape. B represents the wax model or pattern that is embedded within the plaster of Paris investment C in which also the runner hole B' leading to the model from one end of the flask is also formed. D is the plug of fusible metal that is also embedded within the investment C at the inner end of a tunnel E leading out to the other end thereof, and D' is the rod of metal or other material fusible 80 only at a higher temperature than the maximum temperature to which the mold is to be heated, one end of which is held in the plug D so that the rod will extend centrally within the tunnel E, and will then by gravity, 85 fall to one side of the tunnel when the plug D melts and loosens its hold on the rod. 90

In this invention means are combined with the rod D' by which an indication may be also given when the temperature of the flask 100 has been heated to the degree necessary to expel the moisture from the investment. These means consist in a second plug F of a fusible metal or other fusible material that is of such a nature as to fuse at a minimum 105 temperature slightly above that of the boiling point of water, for instance, at 230° Fah., and which plug is arranged on the rod D' at a suitable distance from its end. Or instead of a plug, a disk of the material 110

may be used. This plug or disk then occupies a position within the tunnel E in the molding flask and comes under the action of the heat of the flask so that when such 5 heat reaches the specified degree, the plug or disk will melt and thus show the operator that the mold has reached the required temperature and that all moisture is expelled therefrom. It is necessary that the 10 plug or disk F should be at such a point on the rod D' as to occupy a position well within the mouth of the tunnel and thereby be free from any direct action from the flames of the furnace in which the flask is 15 placed. The melting of the plug or disk F will not in any way affect the rigidity of the rod and its subsequent function.

Referring now to the remaining figures of the drawings which show the form of furnace designed for heating the mold, this is 20 designed to cause the heat from the burners to be evenly distributed around the whole circumference of the flask A and thereby to uniformly heat the whole area of the flask's 25 contents.

The furnace designed comprises a stand G having a flat rectangular open top or platform G' at the opposite ends of which, sockets H are formed. Each of these 30 sockets is adapted to receive the vertical stem J of a flask support J' which support is formed as an arc in which the flask A will rest, as shown in Figs. 5 and 6. The flask is thus supported at its two ends by 35 means of the respective supports and it then extends across the top of the platform G'. The supports are made removable from the sockets H so that different sizes and forms of supports to correspond with the 40 different sizes and shapes of flasks to be heated, may be substituted as required.

The top of the furnace is formed as a 45 cover K of the approximate semi-cylindrical form shown, that is adapted to rest upon the edges of the platform G'. This cover is lined with asbestos lining K' or with other approved insulating material. It therefore encircles the flask A laid upon the supports J' and serves to conserve the heat around 50 such flask. The ends of the flask are positioned adjacent to the ends of the cover and these latter ends are made with sight apertures h therein in a line approximately with the center line of such flask so that the indicating means before described may be 55 viewed without raising the cover. The cover is also formed with a vent or vents h' in its top for the escape of the fumes and to insure of the proper updraft around 60 the surface of the flask.

The lower portion of the stand or frame is made with ledges M arranged at intervals in the height of the stand and which are adapted to receive and support a plate 65 N that carries the burner by which the fur-

nace is heated. The distance of the burner beneath the flask is therefore adjustable at will. The burner is formed with a tubular main O having one or more rows of flame jets O' extending upward therefrom. Two 70 parallel rows are preferably provided as shown in the drawings, those of each row being either slightly inclined outward from those of the other, in order that the flames thereof may be directed on to the respective 75 and corresponding halves of the flask A so as to pass around it and then out to the vent, or arranged in parallel vertical lines and spaced apart so that the flames will impinge upon the flask upon the opposite sides 80 of its center line and then follow the same course around the flask. In this manner the heat will be evenly distributed over the whole circumferential area of the flask, and any undue concentration of the heat upon 85 the one portion thereof will thereby be avoided.

The frame may, if desired, be provided with a gage bar P extending horizontally across it at each end or side and so disposed 90 in relation to the burner that the height of the flames thereof in relation to a sight line extending between the two bars, may be gaged by the operator. The operator, knowing from previous experiment or use, the 95 height of flame in relation to this sight line, that gives best results in the preliminary heating of the mold before referred to, may adjust his flame accordingly, or instead of these bars being attached to the frame, a 100 bar R having a similar purpose may be fixed to the side or end of the burner supporting plate N by means of a vertical stay R' (Figs. 2 and 4) attached to such plate. This bar may be made adjustable in its 105 height by adjusting nuts, or other means, on the lower end of the stay.

The usual air supply aperture or slot S of the burner main may be provided with a 110 regulating sleeve S' (Fig. 4) by means of which the air supply may be adjusted at will.

I claim:

1. In a device for heating metal casting molds, a mold supporting frame consisting 115 in a stand having a horizontal open top with removable mold rests at each end thereof, an insulated cover fitting over such top and adapted to inclose the mold, and a heating burner supported within the lower portion 120 of the stand and adjustable in height thereon, substantially as specified.

2. In a device for heating metal casting molds, the combination with a mold supporting frame having an open horizontal top 125 with removable mold rests at each end thereof, of a burner for heating the mold arranged beneath such open top and formed by a main having jet nozzles arranged in two parallel rows extending upward from 130

such main in respectively oppositely diverging or vertical lines, substantially as specified.

3. In a device for heating metal casting molds, a mold supporting frame mounted on a stand and formed by an open horizontal top with sockets arranged one at each end thereof, and mold rests adapted to support the mold each formed by a curved cross bar 10 and a vertical stem that enters one of the sockets in the frame, substantially as specified.

4. In a device for heating metal casting molds, a mold supporting frame mounted 15 on a stand and formed by an open hori-

zontal top provided with means for supporting the mold thereon and a burner arranged beneath such top and supported by the stand, in combination with an insulated cover fitting over the stand top and formed 20 with vision apertures in its ends, substantially as specified.

In testimony whereof I have signed this specification in the presence of two subscribing witnesses.

ALFRED CHARLES ATKINSON.
